(57) **CLAIM**

The ornamental design for a bumper for a heavy duty truck, as shown and described.

DESCRIPTION

FIG. 1 is a perspective view of a bumper for a heavy duty truck showing the front of our new design;

FIG. 2 is a front view;

FIG. 3 is a top view;

FIG. 4 is a right side view, the opposite side view being a mirror image of that shown; and,

FIG. 5 is a bottom view.

The rear of the bumper is unornamented.
